UNITED STATES PATENT OFFICE.

THOMAS R. KENNEDY AND EDWARD J. KING, OF ROCHESTER, NEW YORK,
ASSIGNORS TO CO-OPERATIVE FOUNDRY CO., OF ROCHESTER, NEW
YORK, A CORPORATION OF NEW YORK.

DESIGN FOR A STOVE.

No. 38,798.

Specification for Design.

Patented Sept. 10, 1907.

Application filed July 31, 1907. Serial No. 386,488. Term of patent 7 years.

To all whom it may concern:

Be it known that we, THOMAS R. KENNEDY and EDWARD J. KING, citizens of the United States, residing at Rochester, in the county of Monroe and State of New York, have invented a new, original, and ornamental Design for Stoves, of which the accompanying drawing is a representation.

The figure is a perspective view of a stove showing our new design.

We claim:

The ornamental design for a stove as herein shown.

THOMAS R. KENNEDY.
EDWARD J. KING.
